Primary Examiner — Elizabeth Albert*(74) Attorney, Agent, or Firm* — Rankin, Hill & Clark LLP(57) **CLAIM**

The ornamental design for a storage unit, as shown and described.

DESCRIPTION

FIG. 1 is an exploded perspective view of a storage unit;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and
FIG. 7 is a bottom plan view thereof; and
FIG. 8 is a perspective view of the storage unit shown assembled.

The broken lines in the drawings are included to show features that form no part of the claimed design.

1 Claim, 8 Drawing Sheets(56)
